C. B. FICKLEN

INDICATOR

Filed March 23, 1928

INVENTOR

Carter B. Ficklen, INVENTOR

ATTORNEY

UNITED STATES PATENT OFFICE.

CARTER B. FICKLEN, OF FORTRESS MONROE, VIRGINIA.

INDICATOR.

Application filed March 23, 1928. Serial No. 264,092.

This invention relates to new and useful improvements in indicators generally, although more particularly to an indicator for use in card games, such as bridge or five hundred, for the purpose of indicating the bids of the different players.

One of the main objects of my invention lies in the provision of a card game indicator for use in either "bridge" or "500" for indicating to the players the character of the bids of the different players.

Another object of my invention lies in a card game indicator of the character described which is provided with "bid" indicia of such a simple nature as to render the same readily legible and extremely easy of operation.

With these and other objects in view which will more fully appear, the nature of the invention will be more clearly understood by following the description, the appended claims, and the several views illustrated in the accompanying drawings.

In the accompanying drawings which illustrate one form of my invention:

Fig. 1 is a plan view of an indicator embodying my invention, and

Fig. 2 is a cross sectional view taken on the line 2—2 of Fig. 1.

Like reference numerals designate corresponding parts throughout the several figures of the drawings.

Referring to the accompanying drawings, my invention includes a board A which comprises top and bottom superposed plates 5 and 6 and an intermediate plate 7, which may be secured together by any suitable adhesive or other means.

The upper edge 8 of the top plate 5 is arcuate and is disposed below and in spaced relation to the upper edge 9 of the bottom plate 6. The intermediate plate 7 is provided with a segmental recess having radial walls 10—10, the recess being located centrally below the top part of the upper plate 5 and opening towards the top of the board.

The board A is provided with "bid" indicia which includes a series of "trick" indicia B and a series of "trump" indicia C, which are common to the card games known as "bridge" and "five hundred."

The "trick" indicia B comprises an arcuate series of consecutive numbers ranging

from 1 to 10 of which the numbers 1 to 7 indicate the range of "trick" bids in "bridge" from minimum to maximum, and the numbers 6 to 10 indicate the range of "trick" bids in "five hundred" from minimum to maximum. This series of "trick" indicia is located on the bottom plate directly above the upper arcuate edge 8 of the top plate 5, and directly above the segmental recess of the intermediate plate 7.

The "trump" indicia C comprises an arcuate series of trump indicating data such as the representations of a club, a diamond, a heart and a spade, as well as other data such as "No bid," "No trumps," "Pass," "Double," and "Redouble." This "trump" indicia is located on the upper portion of the top plate 5 and parallels the arcuate upper edge 8 thereof. Consequently the "trump" indicia C is located directly below the "trick" indicia B.

Journalized on an axis formed by a rivet 11 or the like, are three pointers 12, 13 and 14, the axis or rivet 11 being concentric with the upper edge 8, and the "trick" indicia B and the "trump" indicia C. The pointers 12 and 13 are mounted to oscillate above the top plate 5 and cooperate with the "trump" indicia. The pointer 14 is mounted to oscillate within the recess of the intermediate plate 7, and its limit of oscillation is defined by the side or radial walls 10—10, the angular relation of which embraces the "trick" indicia B.

The top board is also provided with "bridge" score indicia D and "five hundred" score indicia E.

From the foregoing, it will be readily understood that my invention is especially adapted for card games known as "bridge" and "five hundred" for the purpose of indicating the bid of each player in succession whereby all players will be constantly informed of the last bid made by the players.

It is of course to be understood that the details of structure and arrangements of parts may be variously changed and modified without departing from the spirit and scope of my invention.

I claim:

In a card game indicator, the combination with a board having a series of "trump"

indicia thereon, said board including top and bottom superposed plates, and an intermediate plate, said "bid" indicia including a series of "trump" indicia and a series of "trick" indicia respectively arranged one on the bottom plate and the other on the top plate, the intermediate plate being provided with a quadrant shaped cut-out portion, and

a pair of pointers fulcrumed on a common axis on said board for cooperation with the "trump" and "trick" indicia respectively, one of said pointers being movable in the cut-out portion of the intermediate plate. 10

In testimony whereof I hereunto affix my signature.

CARTER B. FICKLEN.
